SHUTTLE BINDER FOR LOOMS

Filed Dec. 28, 1929

UNITED STATES PATENT OFFICE

ELBRIDGE R. HOLMES, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

SHUTTER BINDER FOR LOOMS

Application filed December 28, 1929. Serial No. 417,213.

This invention relates to improvements in shuttle binders for looms and it is the general object of the invention to provide such a device preferably of pressed sheet steel so formed as to cooperate properly with a shuttle.

When a shuttle enters its box with the eye leading, the weft thread lies between the binder and the adjacent wall of the shuttle. 10 It is necessary to provide clearance for the thread, otherwise it will be pinched and broken, and it is an important object of my present invention to reinforce the binder by bending the upper and lower edges thereof 15 toward each other so as to lie on the shuttle side of the binder, the edges being spaced to define a clearance groove for the weft.

It is customary practice to provide a pivot pin for the binder whether the latter be used 20 for instance at the single box end of an automatic loom or at the drop box end of a fancy loom. The binder ordinarily has a very slight angular movement with respect to the lay and in order to obviate the use of a fulcrum it is an important object of my present 25 invention to provide a leaf spring between the relatively fixed part of the shuttle box and the binder, said spring being capable of flexing through the small angle required 30 without danger of breaking.

It is another object of my present invention to locate one end of the supporting spring 35 between the folded top and bottom edges of the binder, this construction locating the slot near the shuttle and at the same time keeping the spring spaced from the thread of the shuttle by a distance equal substantially to the thickness of the stock of which the binder is made.

40 It is another object of my invention to provide a spring mounted binder and a pair of spaced stops to engage it so that the resilience of the binder will act to check the shuttle without placing undue strain on the spring mounting.

With these and other objects in view which will appear as the description proceeds, my invention resides in the combination and arrangement of parts hereinafter described and 45 set forth in the claims.

In the accompanying drawings, wherein a convenient embodiment of my invention is set forth,

Fig. 1 is a front elevation of the drop box end of a loom having my invention applied 55 thereto,

Fig. 2 is a top plan view taken in the direction of arrow 2, Fig. 1,

Fig. 3 is an enlarged front elevation of the 60 binder,

Figs. 4 and 5 are vertical sections on lines 4—4 and 5—5, respectively, of Fig. 3, on an enlarged scale,

Fig. 6 is a vertical section on line 6—6 of 65 Fig. 2, on an enlarged scale,

Fig. 7 is an enlarged horizontal section on line 7—7 of Fig. 1, and

Fig. 8 is a detail vertical section on line 8—8 of Fig. 7.

Referring to Fig. 1, I have shown a lay 70 10 having box guides 11 and 12 which receive, respectively, tongues 13 and 14 on a gang of shifting boxes 15. The inner ends of the boxes are provided with ears 16 which support a vertically extending binder pin 17. 75 The lay has the usual protector rod 18 from which upwardly projects a protector finger 19.

The outer end of the box has a vertical web 80 20 which has rigid therewith a supporting plate 21. The latter may be formed either as an integral part of the box structure or may be secured thereto as a separate piece.

The matter thus far described, with the exception of the securing plate 21, may be 85 substantially the same as that found in the usual form of fancy or drop box loom. As the shuttle S enters the box it will pass into that cell of the gang which is opposite the lay race and lie against the rear wall 22 of the 90 box.

My invention relates to the so-called binder or swell which checks the shuttle as it enters the box and in carrying my invention into effect I provide a binder 30 formed of sheet 95 steel and having a vertical body portion 31 which in this instance is on the outside or front of the binder and opposite the shuttle. The top and bottom edges of the binder are folded over and downwardly as at 32 and 33, 100

respectively, defining a groove 34 which is preferably in horizontal alignment with a groove 35 formed in the shuttle S. In order to provide comparatively smooth corners for the groove 35 I prefer to fold the binder in such a way that the shuttle engaging surfaces 36 and 37 of the bent edges were uppermost in a previous punching operation. In this way the die when descending will form a slight rounding of the corners which later define the groove 35. If this procedure is not followed it will be desirable to remove any burrs which may lie along the edges of the groove to save the shuttle from undue wear.

In order to mount the binder I provide a relatively stiff flat leaf spring 40, a part of which as shown in Figs. 3 and 4 lies between the bent edges 32 and 33 on one side and the wall or body portion 31 on the opposite side. In this way the spring is restrained against lateral displacement and by properly forming the binder with respect to the width of the spring the latter may be held tightly in position so that there is practically no relative motion between the binder and that part of the spring which is inclosed thereby. In order to prevent endwise displacement of the spring I provide rivets or other securing means 41 passing through the binder and spring.

The outer or left end of the spring as viewed in Figs. 1 and 3 may fit snugly in a groove 42 formed in the plate 21. A block 43 has a parallel sided projection 44 which enters the groove 42 and is held thereby against angular motion relative to the plate. A groove 45 is formed in the block 43 to receive the foot 46 of a binder engaging leaf spring 47. A single bolt or screw 48 passes through the binder spring, block and supporting leaf spring 40 and is secured to the plate 21, as by screw threads. In this way a comparatively large area is brought to bear against the leaf springs 40 to hold the same in position independently of any direct contact which the springs may have with their supporting screws or similar devices 48.

With the usual arrangement the shuttle is checked in part by the resilience of the binder itself, and in order to retain this action, I provide a stop pin 50 which passes through ears 51 formed on the gang of boxes. This pin lies in front of the binders and may be normally engaged by them. The binder is formed with a curve 52 the rearmost part of which lies between pins 17 and 50, the binder being out of contact with the shuttle at points immediately behind the pin 50. In this way shuttles of slightly varying widths may be used.

Under normal conditions with the shuttle box empty, the spring 47 and the pressure of the protector finger will hold the binder rearwardly toward the back wall of the shuttle

box against the resistance of the leaf spring 40. The binder will preferably engage the pin 50 and thereby position the inner end of the binder. As a shuttle enters the box it will engage the binder and push it forwardly until the inner end engages the pin 17, the leaf spring 40 flexing to permit such motion. Further motion of the shuttle into the box is resisted by the binder independently of the leaf spring 40.

In order to be able to remove the binder quickly for replacement or adjustment I form the leaf spring 40 with an open longitudinal slot 60 which extends inwardly from the outer or left end as viewed in Fig. 3. By loosening the bolt or screw 48 the binder may be taken out without removing the block 43 or binder spring 47.

From the foregoing it will be seen that I have provided a simple form of pressed steel binder wherein the usual pivot is eliminated and in its place is substituted a spring which returns the binder to normal shuttle checking position. So far as certain phases of my invention are concerned I deem it necessary to have the binder formed of pressed metal, inasmuch as the spring can act satisfactorily independently of the particular form of binder to which it is attached. It will further be seen that the binder is so shaped as to retain the spring in position by integral edges which define between them a space for the thread of the shuttle, the thickness of said ends being sufficient to hold the spring spaced from the thread. Furthermore, the leaf spring is so formed as to be readily removable by reason of the slot 60.

Having thus described my invention it will be seen that changes and modifications may be made therein by those skilled in the art without departing from the spirit and scope of the invention and I do not wish to be limited to the details herein disclosed, but what I claim is:

1. A shuttle binder for a shuttle box having a binder attaching element, said binder having a relatively stiff body to engage the shuttle and having a less stiff spring secured thereto and attached to the element and forming the sole means of support for the binder with respect to the box, said relatively stiff body overlapping the spring and held by the latter against angular motion.

2. A shuttle binder for a shuttle box having a binder attaching element, a binder formed of sheet metal bent so as to have the upper and lower edges thereof extending toward each other, and a flat spring located between the bent edges and held fixed to the binder by said edges, said spring being attached to the element and forming the principal means of support for said binder and said spring flexing as the binder is moved by the shuttle.

3. A shuttle binder for a shuttle box having

a binder attaching element being formed of sheet metal bent so as to have the upper and lower edges thereof extending toward each other, said binder having a relatively stiff body to engage the shuttle and having a less stiff spring secured thereto and attached to the element and forming the principal means of support for the binder with respect to the box, the bent edges defining between them a groove for the thread of the shuttle.

4. In a loom shuttle box having an attaching portion, a binder for the shuttle having a relatively stiff body, a substantially flat leaf spring secured to the binder and possessed of less stiffness than the body, and means to secure one end of said spring to the attaching portion of the shuttle box, said spring being the principal support for the binder and flexing with the binder as the latter is moved with the shuttle, said relatively stiff body having a portion overlapping the secured part of the flat leaf spring to resist any angular motion between the stiff body and leaf spring.

5. A shuttle box for a loom, an attaching plate rigid with the relatively stiff shuttle box, a shuttle binder, a less stiff leaf spring secured at one end to the binder, means to secure the other end of the leaf spring to the attaching plate, said spring forming a non-pivotal resilient support for the binder and moving with the latter as the shuttle enters a box, said relatively stiff binder overlapping the spring and held by the latter against angular motion.

6. A shuttle binder for a loom formed of pressed metal, said binder having a substantially vertical body portion and having the top and bottom edges thereof bent along substantially horizontal lines to lie substantially parallel to the body portion, said edges forming shuttle engaging portions of the binder and being separated to define a groove for the thread of the shuttle.

7. A shuttle binder formed of pressed metal and having a body the top and bottom edges of which are bent along lines extending longitudinally of the binder to form reinforcing edges, the latter being spaced to define a longitudinally extending thread groove.

8. A shuttle binder formed of pressed metal and having a body the top and bottom edges of which are bent along lines extending longitudinally of the binder to form reinforcing edges the latter being spaced to define a longitudinally extending thread groove, and a resilient supporting member located between the bent edges and the body of the binder and forming part of the binder by means of which the latter may be supported.

9. In a loom, a shuttle box, a relatively stiff shuttle binder, and a less stiff supporting means between the binder and box forming the only support for the binder, said means

overlying a portion of the binder and coacting therewith to resist angular motion thereof.

In testimony whereof I have hereunto affixed my signature.
